W. D. WINDERS

LOOSE LEAF BINDER

Filed May 6, 1925

Inventor

W. D. Winders

Attorney

UNITED STATES PATENT OFFICE.

WILLIAM DALE WINDERS, OF COLUMBUS, OHIO, ASSIGNOR TO HENRY C. MILLER, OF MILWAUKEE, WISCONSIN.

LOOSE-LEAF BINDER.

Application filed May 6, 1925. Serial No. 28,301.

To all whom it may concern:

Be it known that I, WILLIAM DALE WINDERS, a citizen of the United States, residing at Columbus, in the county of Franklin and State of Ohio, have invented certain new and useful Improvements in Loose-Leaf Binders, of which the following is a specification.

This invention relates to improvements in loose leaf binders, and has for its principal object the provision of improved and simplified structure by means of which a plurality of sheets may be clamped and securely held between a pair of binding members or strips so that the sheets may be securely maintained in a bound book like form.

The invention consists in the provision of improved means for effecting relative approach between the clamping members or strips of the holder which includes a flexible post anchored to one of said strips and guided through an internally threaded sleeve arranged for rotation in the other of said strips, one end of said post being provided with a threaded terminal arranged for cooperation with said sleeve, whereby upon the rotation of the sleeve, effected through a convenient manual control, the threaded terminal may be moved longitudinally within said sleeve to regulate the effective length of the flexible post.

For a further understanding of the invention reference is to be had to the following description and the accompanying drawings, wherein:

Figure 1 is a vertical longitudinal sectional view taken through the improved loose leaf binder comprising the present invention,

Figure 2 is an enlarged horizontal sectional view taken on the plane indicated by the line 2—2 of Figure 1,

Figure 3 is a vertical transverse sectional view on the line 3—3 of Figure 1,

Figure 4 is a similar view on the line 4—4 of Figure 2,

Figure 5 is a detail perspective view of one end of the flexible post,

Figure 6 is a similar view of the guiding sleeve,

Figure 7 is a fragmentary view of the magazine, and

Figure 8 is a vertical section taken through the magazine and post member.

Referring to the drawings the numeral 1 designates my improved loose leaf binder in its entirety. This binder consists of upper and lower clamping strips or members 2 and 3 respectively, which in this instance are of hollow metallic construction. Associated with the strips are hinged covers 4—4, which are united with the strips 2 and 3 by means of straps 5, pivoted as at 6 in connection with said strips so that the covers may swing through an arc of substantially 180 degrees to provide complete access to the sheets or leaves 7 clamped between the strips.

The relative adjustment of the strips 2 and 3 is effected by the provision of a plurality of flexible posts 8. These posts each consist of a number of short metallic cylindrical sections 9, each having one end thereof provided with a tongue extension 10 and the other end with a slot or recess 11 in which is received the tongue extension of the next adjoining section. Pivot pins 12 pass through the sections 9 to pivotally secure each of the extensions 10 within their respective slots 11. By this construction a substantial post is provided but flexibility secured, as shown in Figure 1. Arranged within the hollow body of the lower strip 3 are blocks or bearings 13, which are provided with longitudinally aligned openings 85 for the reception of magazines 14. These magazines are located so as to extend longitudinally of the lower strip 3 and in this instance are of hollow tubular form. In internal diameter the magazines are of substantially the same diameter as the posts 8. The inner ends of the magazines are spaced relatively and are provided with sockets 15, in which are positioned the ends of a coil spring 16. This spring normally serves to maintain the magazines relatively separated. The inner ends of said magazines are provided with down-turned manipulating extremities 17, accessible through an opening 18 provided in the lower part of the strip 3. Obviously, by gripping the extremity 17 between the fingers, the tubes may be moved relatively to accomplish a purpose herein-after set forth.

The outer ends of the magazines are provided with enlarged slots 19, which terminate in relatively reduced slotted portions 20. The slots 19 are of sufficient width to per-

mit the posts 8 to pass therethrough, while the restricted portions 20 are of a diameter materially less than the diameter of the posts 8, but of sufficient width to permit of 5 the passage of the tongue extensions 10. By this arrangement it will be seen that when it is desired to adjust the effective length of the flexible posts, the magazines are drawn axially together, so that the slots 19 10 will be brought into registration with the vertically arranged openings 21 provided in the blocks 13. When this registration is secured the posts may be withdrawn at will from the magazine, and when the magazines are released, the latter respond to the influence of the spring 16 and bring the restricted slots 20 into registration with the openings 21. By this construction the flexible posts are then anchored at their lower 15 ends in secured relation with the anchor blocks, and more minute adjustment is obtained by the mechanism provided in the upper strip 2.

The post sections extend upwardly and 20 are trained through curved guides 18' provided in the upper strip 2 so that the posts will extend substantially horizontally within in the upper strip or at right angles to that portion lying between the strips 2 and 3. 25 The upper end of each of the posts terminate in a threaded terminal or nut 19', which is disposed to engage with internal screw threads 20' provided within a rotatably mounted sleeve 22, that is mounted for rotation 30 within journals 23 provided in the upper strip. It will be manifest that when the sleeve 22 is rotated the nut 19' will be caused to traverse the sleeve longitudinally, thereby regulating the effective length of the flexible posts so as to control the distance 35 between the strips at will. It will be understood that the internal threads 20' provided within the sleeve 22 are of the right and left hand variety so that upon rotation of the 40 sleeve both post sections will be simultaneously lengthened or contracted. To effect the rotation of the sleeve 22 the latter is provided mid-way of its length with external gear teeth 24, which engage with similar teeth 45 provided on a spur wheel 25. The wheel 25 is mounted on a shaft 26, journaled in connection with the upper strip. The shaft 26 extends to a point exterior of said strip and is provided with a squared portion to 50 which may be applied a manipulating key.

In view of the foregoing description it will be seen that, in operation, the rotation of the shaft 26 will result in the rotation of the sleeve 22. This movement on the part of 55 the sleeve causes the threaded terminal sections 19' of the flexible posts 8 to traverse the sleeve or tube longitudinally, and since the sections 9 are flexibly related to and connected with the terminal sections 19', it follows that the distance between the strips 2

and 3 may be readily varied and regulated. By the use of the screw threads a very considerable leverage can be brought to bear on the sheets clamped between the strips 2 and 3 to positively hold the latter within 70 the binder, and furthermore, a construction is provided which is very simple and easy to control and operate. Again, the use of the screw threads results in the locking of the terminal sections or nuts 19 at any set 75 position of adjustment, the same serving as an automatic lock to prevent undue movement or loss in position of the post sections.

A sleeve 27 as shown in Figures 2 and 3, may be provided around the upper ends of 80 the flexible posts 8. Each of these sleeves is arranged within the outer sleeves 22 and is fixed in connection with the upper strip 2, and serves to prevent rotation on the part of the flexible shaft when the sleeves 22 are 85 revolved. Thus, the present invention provides a rough or general adjustment in the lower strip and a firm clamping adjustment in the mechanism of the upper strip. By this construction a binder is provided which 90 can be admirably used in connection with ledgers or the like which vary widely in thickness.

What is claimed is:

1. In a binder, a pair of hollow clamping strips, flexible binding posts fixed to one of said strips, adjustable take up mechanism provided in the other of said strips and cooperative with said posts for varying their effective lengths, said mechanism comprising 95 a rotatable sleeve having internal right and left threaded portions, and nuts carried by certain of the ends of said posts and cooperative with the right and left threaded portions of said sleeve to traverse the sleeve 100 longitudinally upon rotation of said sleeve.

2. In a loose leaf book or ledger, the combination with a pair of binding members movable toward and from each other to clamp leaves between them and release the 110 same respectively, a sleeve carried by one of said members and including internally disposed right and left threaded portions, a pair of flexible posts fixed to one of said members at certain of their ends and having 115 the other ends thereof threaded for cooperation with the internally threaded portions of said sleeve, and manually operated means for effecting the rotation of said sleeve.

3. In a loose leaf binder, a pair of clamp- 120 ing members, flexible posts having certain of their ends connected rigidly with one of said members, the other ends of said posts being adjustably connected with the other 125 of said members, said connection comprising a pair of sleeves journaled for rotation within one of said members, said sleeves being internally threaded, nuts carried by said posts and cooperative with said threads 130 to traverse the sleeves longitudinally when

the latter are rotated, and manually operated means for effecting the rotation of said sleeves.

4. In a loose leaf binder, a clamping member, a magazine movably mounted within said clamping member, a flexible post contained within said magazine and locking means operated by variations in position of said magazine to control the withdrawal of said post from said magazine.

5. In a loose leaf binder, a clamping mem-

ber, a pair of magazines slidably mounted within said clamping member, flexible posts mounted in said magazines, guide outlets arranged laterally of said magazines through which said posts pass from said member, and manually operated means for effecting relative longitudinal approach between said magazines to permit of the withdrawal of said posts through said guide outlets.
